Samuel C. Fredson.

UNITED STATES PATENT OFFICE.

SAMUEL CARL FREDSON, OF WOOSUNG, ILLINOIS.

BOUQUET-HOLDER.

SPECIFICATION forming part of Letters Patent No. 605,543, dated June 14, 1898.

Application filed November 10, 1897. Serial No. 658,085. (No model.)

To all whom it may concern:

Be it known that I, SAMUEL CARL FREDSON, a subject of the King of Denmark, residing at Woosung, in the county of Ogle and State of Illinois, have invented a new and useful Bouquet-Holder, of which the following is a specification.

This invention relates to bouquet-holders especially designed for attachment to a bicycle, its object being to provide an efficient and simple device of this character adapted to be detachably connected to a bicycle and carrying pads of absorbent material, between which the stems of the flowers are clamped.

With these objects in view the invention consists of the several details of construction and combination of parts, as will be herein-after fully described, and particularly pointed out in the claims.

In the drawings, Figure 1 is a side elevation of a bicycle, showing my improved bouquet-holder in position on the handle-bar. Fig. 2 is a perspective view of the holder and clamp, the holder being open. Fig. 3 is a sectional detail showing the manner of connecting the clamp to one of the sections of the holder. Fig. 4 is a bottom plan view of the holder, the clamp being in a position to be secured to a vertically-disposed support. Fig. 5 is a sectional detail of the locking device at the upper end of the sections.

Similar reference-numerals indicate similar parts in the several figures.

The bouquet-holder is formed of two opposing trough-shaped sections, (indicated by 1 and 2, respectively,) the edges of one section overlapping the edges of the other section, as best shown in Fig. 4, and when secured together the two sections will form a tube. As shown in the drawings, the holder is rectangular in cross-section; but it may have other cross-sectional form, as will be readily understood. The sections will preferably be formed of sheet spring metal and be hinged together at their lower ends, preferably on a pin 3, which extends across the holder. Instead of a pin two rivets may be used for this purpose; but the pin is preferable, as it serves also to support the lower ends of the absorbent pads 4, one of which is loosely seated in each section.

Small tongues 5 are struck out from the edges of one section, and these tongues are adapted to fit in openings 6 in the edges of the other section and detachably lock the upper ends of the sections together. These locking devices can be easily disconnected by pressing the edges of the section which are inside the edges of the other section toward each other, as will be readily understood, and it will be immaterial whether the tongues are on the inner or the outer edges. Preferably a boss 7 will be secured on the inner face of one section near its center and be provided with a threaded opening 8 for the reception of a screw 9, which secures the clamp to the holder.

As illustrated, the clamp is made of two sections, (indicated by 10 and 11, respectively,) each section having a middle curved portion 70 to fit around a cylindrical support, such as the handle-bar or the fork-stem of a bicycle, and straight end portions which have openings for the reception of the clamping-screws 12, the openings in the section 10 being 75 threaded. It is obvious that the two sections may be hinged together at one end, if preferred, and only one clamping-screw be employed. The curved portion of the section 10 is depressed or offset to form a flat bearing-surface (indicated by 13) and is perforated for the passage of the screw 9. The head of the screw 9 will be wholly within the depression and will not interfere with or be in contact with the cylindrical support. A 85 washer 14, of rubber or yielding material, is interposed between the bearing-surface 13 and the holder, and when the screw 9 is set up tight will prevent the holder from turning on the clamp, or vice versa; but by loosening 90 the screw 9 it is obvious that the clamp may be turned on the screw to adjust it for attachment to either a vertically-disposed support or a horizontally-disposed support.

The clamp will be secured on the handle-bar or the fork-stem of the bicycle, as preferred, and may thus form a permanent attachment to the bicycle. When it is desired to insert a bouquet into the holder, the edges of the section which are inside will be pressed 100 toward each other slightly to disengage the locking devices, and the holder can then be

opened, as indicated in Fig. 3, after which the stems of the flowers can be put in position and the holder closed, which will have the effect of clamping the stems between the 5 absorbent pads, which latter will form a yielding support for the stems, it being of course understood that the pads will have been previously moistened. In this manner the flowers can be kept in a fresh condition for a considerable length of time.

It will be understood that changes in the form, proportion, and the minor details of construction may be resorted to without departing from the spirit or sacrificing any of 15 the advantages of this invention.

Having thus described the invention, what I claim is—

1. A bouquet-holder formed of two opposing trough-shaped sections arranged to clamp 20 positively the stems of flowers, the edges of which sections overlap each other and are hinged together at their lower ends and provided with interlocking devices at their upper ends, said sections forming a tube when 25 locked together, and a pad of absorbent material supported in each section, said pads forming a yielding clamp for the stems of the flowers, substantially as described.

2. A bouquet-holder formed of two opposing trough-shaped sections formed of spring 30 sheet metal and arranged to clamp positively the stems of flowers, the edges of which sections overlap each other and are hinged together at their lower ends, and provided with 35 interlocking devices at their upper ends adapted to be sprung into or out of engagement, said sections forming a tube when locked together, and a pad of absorbent material supported in each section, said pads

forming a yielding clamp for the stems of the 40 flowers, substantially as described.

3. A bouquet-holder formed of two opposing trough-shaped sections, the edges of which overlap each other and are hinged together at their lower ends and provided with interlocking devices at their upper ends, said sections forming a tube when locked together, and a pad of absorbent material supported 45 in each section, said pads forming a yielding clamp for the stems of the flowers, combined with a clamp adjustably connected to one of the sections of said holder, substantially as described.

4. A bouquet-holder comprising two substantially trough-shaped sections closed at 55 their lower ends and hinged together at that point at the inner edges of the sections, said sections being adapted to swing apart and capable of positively clamping the stems of the flowers, substantially as described.

5. A bouquet-holder comprising two substantially trough-shaped sections hinged together at their lower ends adjacent to their inner edges and adapted to swing apart, and the absorbent pads mounted within the 65 trough-shaped sections and adapted to engage the stems of flowers, whereby the latter are supplied with moisture and a yielding engagement is effected, substantially as described.

In testimony that I claim the foregoing as my own I have hereto affixed my signature in the presence of two witnesses.

SAMUEL CARL FREDSON.
